UNITED STATES PATENT OFFICE.

HARRY J. FORD, OF SAN QUENTIN, CALIFORNIA, ASSIGNOR OF ONE-HALF TO WILLIAM JOHN HILL.

ELECTRIC SWITCH.

1,006,193.

Specification of Letters Patent. Patented Oct. 17, 1911.

Application filed April 18, 1911. Serial No. 621,915.

To all whom it may concern:

Be it known that I, HARRY JOHN FORD, a citizen of the United States, residing at San Quentin, in the county of Marin and State of California, have invented new and useful Improvements in Electric Switches, of which the following is a specification.

This invention relates to switch-operating mechanisms and relates more particularly to a mechanism including electro-magnets or solenoids for operating the switch points to open and close the track switch.

The invention has for one of its objects to improve and simplify the construction and operation of switch-operating mechanisms of this character so as to be reliable and efficient in use, comparatively simple and inexpensive to manufacture and install, and readily controlled from a remote point such as a signal tower, station or the like.

Another object of the invention is the provision of a novel arrangement of an electro-magnetically operated element connected with the switch points, in combination with electro-magnetically operated combined locks and circuit closers whereby the said element is first released and then operated by one of the operating solenoids that is connected in circuit upon the unlocking of the element in a manner to be more fully described hereinafter.

With these objects in view and others, as will appear as the description proceeds, the invention comprises the various novel features of construction and arrangement of parts which will be more fully described hereinafter and set forth with particularity in the claims appended hereto.

In the accompanying drawing, which illustrates one embodiment of the invention, Figure 1 is a plan view of a track switch with the operating mechanism installed in relation thereto. Fig. 2 is a partly diagrammatic and partly sectional view of the releasing and actuating solenoids or magnets and their circuit connections.

Similar reference characters are employed to designate corresponding parts throughout the views.

Referring to the drawings, 1 and 2 designate the main track rails, and 3 and 4, the rails of the siding, cross-over or the like, that are related to the main rails by switch points 5 and 6, said points being suitably connected together by one or more rods 7,

so that both switch points or tongues will move in parallelism in opening or closing the switch.

The switch points are moved to open or closed position by a bar or equivalent element 8 extending transversely of the track with its ends operatively related to both switch points so that movement in one direction will open the switch and movement in the opposite direction will close the switch. The bar 8 passes through separate solenoids or electro-magnets 9 and 10, which are of any suitable construction and are fastened rigidly in the roadbed in any desired manner, and on the rod 8 are armatures or cores 11 and 12 for the respective operating magnets 9 and 10. Obviously, when one electro-magnet or solenoid is energized, the core or armature thereof will be attracted while the core or armature of the other electro-magnet or solenoid will be moved away from the latter, so that at all times one electro-magnet is in condition to be energized for opening or closing the switch by attracting its armature.

The switch-operating element 8 is normally locked against movement by one of two electro-magnetically operated locks. For this purpose the element or bar 8 has notches 13 and 14 or equivalent means with which are adapted to engage locking bolts 15 and 16. Each bolt is provided with an armature or core 17 operated by a solenoid or electro-magnet, the electro-magnets being designated 18 and 19, respectively. The recesses 13 and 14 are spaced apart a shorter distance than are the locking bolts 15 and 16, so that only one of the latter will be engaged in a recess, and when the operating element 8 is thus engaged by a locking point, the switch points will be in either open or closed position. These bolt-operating or releasing solenoids 18 and 19 are adapted to be arranged in separate circuits under the control of the signal man in the tower or at a station, so that the switch-operating mechanism can be released to open or close the switch. The releasing of either bolt is intended to connect in circuit the appropriate operating electro-magnet 9 or 10, and consequently each bolt has a bridging contact 20 adapted to engage contact points 21 and 22, thus constituting a circuit closer.

At the station or tower are arranged

switches 23 and 24 that are connected, respectively, by wires 25 and 26 with the solenoids 18 and 19, the solenoids being connected to ground at 27 and 32. The switches 23 and 24 are connected with a suitable source of current such as a battery 28 that has one terminal connected to ground at 29. Thus, when the switch 24 is closed, current will flow from the battery through the wire 26, 10 solenoid 18, grounds 27 and 29, and battery 28. The bolt 15 is thus operated to release the switch-throwing element 8 and at the same time the circuit closer completes a circuit through the electro-magnet 10 by 15 means of a branch wire 25^a, contacts 21, 20 and 22, wire 30, right hand solenoid 10, and ground 31. The ground return or negative side of the battery may consist of the track rails. When the solenoid or electro-magnet 20 10 is thus energized, the switch-throwing element 8 moves to the right until the bolt 16 drops into the recess 14 of the element 8. The switch 24 is now opened so that waste of current will be prevented and the switch 25 points will remain locked in the position to which they have been thrown and upon the opening of the circuit the solenoid 18 is deenergized so that its bolt 15 can drop against the element 8.

30 When the track switch is to be returned to its former position, the switch 25 is closed so that current will flow through the wire 25, electro-magnet or solenoid 19, and grounds 32 and 29, and battery 28. The 35 solenoid 19 is thus energized to release the bolt 16 and at the same time close the circuit of the left electro-magnet or solenoid 9 through the wire 26^a, contacts 21, 20 and 22, wire 34, grounds 35 and 29, and battery 28. If desired, signal lights 36 and 37 may 40 be connected in circuit with the electro-magnets so as to indicate the condition of the track switch, one light being intended to indicate that the switch is open and the other 45 that the switch is closed.

From the foregoing description, taken in connection with the accompanying drawing, the advantages of the construction and of the method of operation will be readily apparent to those skilled in the art to which the invention appertains, and while I have described the principle of operation of the invention, together with the apparatus which I now consider to be the best em-

bodiment thereof, I desire to have it understood that the apparatus shown is merely illustrative, and that such changes may be made when desired as are within the scope of the claims appended hereto.

Having thus described the invention, 60 what I claim as new, is:—

1. The combination of a track switch, opposed electrical means for opening and closing the switch, separate locking bolts for respectively holding the switch in open or 65 closed position, circuit-closing means associated with the bolts, and separately controlled electrical means for releasing each bolt and closing the associated circuit closer to connect one of the first-mentioned electrical means to open or close the track switch.

2. The combination of a track switch, opposed electro-magnets, a bar connected with the track switch and carrying the cores of 75 the electro-magnets, locking bolts operatively related with the said bar whereby one bolt holds the bar against movement when the track switch is opened or closed, a circuit closer controlled by each bolt, electro- 80 magnets for operating the bolts and controllable circuits for separately energizing the last-mentioned electro-magnets to release the bolts and close the circuit closers to connect the first-mentioned electro-magnets in 85 circuit to open or close the track switch.

3. The combination of a track switch, oppositely-disposed operating electro-magnets or solenoids, a switch-throwing element extending through the solenoids, cores on the 90 element, combined locking devices and circuit closers for locking the element in either extreme position of movement and for energizing either operating solenoid, a solenoid 95 for operating each locking device and circuit closer, separate circuits for the last-mentioned solenoids, and a switch for closing each circuit to energize the solenoid thereof and thereby connect one of the operating solenoids in circuit to operate the 100 track switch.

In testimony whereof I affix my signature in presence of two witnesses.

HARRY J. FORD.
